WASTE RECEPTACLE OR SIMILAR ARTICLE

Christopher B. Wright, P.O. Box 1331,
Chapel Hill, N.C. 27514

Substituted for abandoned design application Ser. No.
78,960, Mar. 11, 1964. This application Aug. 3, 1965,
Ser. No. 86,422

Term of patent 14 years

(Cl. D58—17)

FIG. 1 is a perspective view of a waste receptacle or similar article, showing my new design;

FIG. 2 is an exploded perspective view thereof showing the cover removed therefrom;

FIG. 3 is a side elevational view thereof;

FIG. 4 is a top plan view thereof.

I claim:

The ornamental design for a waste receptacle or similar article, substantially as shown.
